UNITED STATES PATENT OFFICE.

GILBERT M. WISSMAN, OF WASHINGTON, DISTRICT OF COLUMBIA.

FOLDING BED.

1,305,857.

Specification of Letters Patent. Patented June 3, 1919.

Application filed March 18, 1919. Serial No. 283,311.

To all whom it may concern:

Be it known that I, GILBERT M. WISSMAN, citizen of the United States, residing at Washington, in the District of Columbia, 5 have invented certain new and useful Improvements in Folding Beds; and I do declare the following to be a full, clear, and exact description of the invention, such as will enable others skilled in the art to which it appertains to make and use the same.

10 My invention has for its object to provide a simply constructed and inexpensive child's bed or crib which may be quickly and easily folded with the mattress and bedding thereon, and placed beneath an ordinary bed when not in use, after the fashion of the trundle beds once commonly used, provision being made whereby the bed may be opened with ease when required.

15 With the foregoing in view, the invention resides in the novel features of construction and unique association of parts hereinafter fully described and claimed, the descriptive matter being supplemented by the accompanying drawings.

20 Figure 1 is a perspective view of a bed constructed in accordance with my invention, the detachable sides being removed.

Fig. 2 is a side elevation showing the bed 25 in folded or collapsed position.

Fig. 3 is a side elevation of the bed extended for use with the removable sides attached.

Fig. 4 is a detail perspective view showing 30 the manner in which the supporting legs of the mattress frame are mounted.

Fig. 5 is a perspective view showing one 35 of the sliding bars employed for initially starting the legs on their folding movement.

Fig. 6 is a detail perspective illustrating 40 an extension leg which may be employed if desired.

In the drawings above briefly described, the numeral 1 designates a suitably constructed base frame, preferably of rectangular formation with vertical posts 2 at its corners, provided with casters or the like. 45 The posts 2 are by preference braced by blocks or other suitable means 4 to the side bars 5 of the frame and these side bars form tracks as will hereinafter appear, the ends of the bars in question having inclined surfaces 6 and depressed seats 7 at the upper ends of said inclined surfaces, the surface 6 50 at one end of each bar being in downwardly converging relation with a corresponding

surface at the other end thereof. The end bars 8 of the frame 1 may well be tied together by a central longitudinal bar 9 and may be connected with said bar 9 by oblique braces 10. It is to be understood, however, that this construction need not be too closely followed since other adequate arrangements might well be employed.

Hinged at 11 to the posts 2, if the frame 65 1 be provided with such posts, are the head and foot sections 12 and 13 of the bed, said sections being downwardly foldable to the position of Fig. 2 when the bed is not in use. A mattress frame 14, preferably having a 70 spring 15 is disposed above the base frame 1 and by means of links or other adequate means 16, said mattress frame is connected with the head and foot sections 12 and 13 in such a manner as to be lowered when said 75 sections are folded downwardly, and raised for use when said sections are moved upwardly to vertical positions. Appropriate sides 17 are provided for the bed and may be detached when the latter is to be folded. 80 When this is done, the sides 17 may well rest either on the folded head and foot sections 12 and 13, or upon the mattress and bedding.

85 Preferably used in connection with the features above described, are legs 18 connected by spring hinges 19 to the ends of the mattress frame 14, the springs of said hinges having a tendency to swing the legs outwardly to operative position as seen in Figs. 1 and 3. The lower ends of the legs 18 are 90 preferably tied together by transverse bars 20 and may well be provided with rollers 21. These rollers are normally received in the seats 7 so that there is no possibility of the legs folding inwardly by accident. When 95 the rollers are disengaged from the seats 7, however, and allowed to rest upon the inclined surfaces 6 of the tracks 5, downward movement of the mattress frame 14, by inward folding of the head and foot sections 100 of the bed, will cause said legs to fold by the traveling of the rollers 21 along the tracks.

105 For removing the rollers 21 from the seats 7 and initially starting them toward their folded positions as illustrated in Fig. 2, I by preference employ a manually operated trip mechanism which may be of any suitable construction. For illustrative purposes, I have shown a foot lever 22 fulcrumed at 110 23 to the tie bar 9, and a pair of longitudinal bars 24 pivoted to said lever on opposite

sides of its fulcrum. The bars 24 may pass slidably through suitable guides 25 of any suitable construction which are shown carried by the braces 10, and the outer ends of said bars are provided with vertical projections 26 to either contact directly with the tie bars 20 or with plates 27 depending therefrom. The lever 22 and the bars 24 are normally held in an idle position by a coil spring 28, but when said lever is shifted by the foot, the projections 26 of the bars 24 strike the plates 27 or the bars 20 as the case may be, and thus so swing the legs 18 as to disengage their rollers 21 from the seats 7 and position them upon the inclines 6 as shown in dotted lines in Fig. 3. Inward movement of the head and foot sections 12 and 13 will now depress the frame 15, through the instrumentality of the links 16, and such depression will cause the rollers 21 of the legs 18 to travel along the tracks 5, thus allowing folding of the entire bed.

If desired, the pintles 29 of the hinges 11 may extend throughout the width of the bed and carry springs 30 which assist in moving the head and foot sections upwardly to vertical position, thus providing a device which is extremely easy to operate. This ease of operation may also be attributed to a large extent, to the spring hinges 19 which have a tendency to throw the legs 18 outwardly to operative positions.

In folding the bed, it is not necessary to remove the mattress or bedding, but the sides 17 are detached and may if desired be laid upon the bedding. The trip mechanism of the legs 18 is now operated by the foot lever 22 and at the same time the head and foot sections 12 and 13 are folded downwardly. The bed then stands in the collapsed condition illustrated in Fig. 2 and if the sides 17 were not placed within the folded structure, they may well rest upon the head and foot sections as shown in this figure. The entire device is now of such size as to permit reception thereof beneath an ordinary bed so that when it is not in use, it need occupy no unnecessary space, this being of great advantage in comparatively small bed rooms.

All that is required to open the bed for use, is to pull upwardly on the head and foot sections 12 and 13. This raises the mattress and bedding to the proper position and the legs 18 are automatically shifted to vertical positions and engaged with the seats 7, by the spring hinges 19.

In some instances, extension legs 31 having casters or the like 32, might well be provided for the posts 2, in order that the height of the bed may be so varied as to dispose its mattress in approximately the same plane with the mattress of a larger bed. Each leg 31, as seen clearly in Fig. 6, is preferably formed of a length of angle iron to receive

the posts 2, one flange of said angle iron leg being formed with notches 33 adapted to engage the transverse bar 8. Bolts or the like 34 are provided for holding the legs in place and it will be seen that by adjusting 70 the legs to position the bars 8 in the proper notches 33, the height of the bed may be readily varied.

If desired, hooks 35 may be provided for holding the legs 18 in vertical position, and 75 these hooks may well be so located as to be released by the foot of the operator. The hooks 35 may be used in addition to the seats 7, these seats may be used without the hooks, or the latter may be employed without the 80 former, and in fact any adequate means may be used for holding the legs 18 in proper vertical position.

From the foregoing, taken in connection with the accompanying drawings, it will be 85 seen that although my invention is of extremely simple and inexpensive nature, it will be of great advantage and in every way desirable, and since excellent results may be obtained from the details disclosed, they 90 may well be followed, but it is to be understood that within the scope of the invention as claimed, numerous minor changes might well be made.

I claim:

1. In a folding bed, a base frame, head and foot sections hinged to said base frame for downward folding, a mattress frame, means for lowering said mattress frame when said foldable sections are lowered, and 100 for raising said mattress frame when said sections are raised, and foldable legs for supporting said mattress frame from said base frame when the former is elevated for use.

2. In a folding bed, a base frame, head and foot sections hinged to said base frame for downward folding, a mattress frame, means for lowering said mattress frame when said foldable sections are lowered and for raising said mattress frame when said sections are raised, foldable legs hinged to said mattress frame to rest on said base frame when said mattress frame is elevated for use, and seats on said frame for the lower 110 ends of said legs to normally hold them against folding.

3. In a folding bed, a base frame, head and foot sections hinged to said base frame for downward folding, a mattress frame, means for lowering said mattress frame when said foldable sections are lowered and for raising said mattress frame when said sections are raised, foldable legs for supporting said mattress frame in elevated position for use, said legs being foldable by lowering of said mattress frame after they are initially started, and a manually operated trip mechanism for so starting said legs on their folding movement.

4. In a folding bed, a base frame, head and foot sections hinged to said base frame for downward folding, a mattress frame, means for lowering said mattress frame, when said foldable sections are lowered and for raising said mattress frame when said sections are raised, foldable legs hinged to said mattress frame and adapted to rest on said base frame when the former is elevated for use, seats on said base frame for receiving the lower ends of said legs, said legs being foldable by downward movement of said mattress frame when removed from said seats, and a manually operated trip mechanism for so removing said legs from the seat.
5. In a folding bed, a base frame, head and foot sections hinged to said base frame for downward folding, a mattress frame, means for lowering said mattress frame when said foldable sections are lowered and for raising said mattress frame when said sections are raised, legs hinged to said mattress frame and adapted to rest on said base frame when the former is elevated for use, transverse bars connecting the legs at each end of the mattress frame, said legs being inwardly foldable by downward movement of said mattress frame after said legs are initially started, a foot lever fulcrumed to the base frame, and oppositely extending bars pivoted to said lever on opposite sides of its fulcrum and having means to engage the aforesaid transverse bars for initially starting said legs on their folding movement when said foot lever is operated.
6. In a folding bed, a base frame including longitudinal tracks having inclined surfaces at their ends and seats at the upper ends of said inclined surfaces, the surface at one end of each track converging downwardly with that at the other end thereof, a vertically movable mattress frame above said base frame having hinged legs engaging said seats when said mattress frame is elevated for use, and downwardly foldable head and foot sections hinged to said base frame and connected to said mattress frame for either raising or lowering the latter, the aforesaid legs being inwardly foldable by lowering of said mattress frame after said legs are disengaged from said seats and engaged with said inclined surfaces.
7. In a folding bed, a base frame including corner posts and longitudinal tracks, downwardly folding head and foot sections hinged to said corner posts, a mattress frame having hinged inwardly folding legs resting on and adapted for movement along said tracks of the base frame, and inclined links pivoted at their upper ends to said head and foot sections and at their lower ends to said mattress frame.

In testimony whereof I have hereunto set my hand.

GILBERT M. WISSMAN.
